SOAP COMPOSITIONS

Jack Leben, Bushey, England, assignor to Ormuf
Products, Limited, London, EnglandNo Drawing. Application December 15, 1933,
Serial No. 702,643. In Great Britain December
21, 1932

2 Claims. (Cl. 87—5)

This invention relates to compositions of matter containing soaps, the word soap being used hereinafter as indicating alkali metal compounds of fatty acids or sulphonation products or derivatives thereof.

One of the objects of the invention is to provide compositions of matter possessing quick and copious and yet lasting lathering properties.

A further object of the invention is to provide compositions of matter adapted to be employed for the purposes to which soaps are normally employed and particularly compositions of matter containing soaps possessing a high degree of stability in storage and use and which, for instance, do not develop rancidity whereby, for instance, in the production of perfumed saponified compositions a change in odor will be avoided and the employment of large proportions of masking perfumes rendered unnecessary.

A still further object of the invention is to provide compositions of matter adapted for use as detergents and other purposes to which soaps are applied which in the presence of water are more resistant to hydrolysis and which will not saponify or otherwise decompose fatty matter.

The invention is based upon the observation that the foregoing objects may be achieved by the incorporation with alkali-metal salts of higher fatty acids, of a proportion of alkyloamine salts of aromatic carboxylic acids.

The alkyloamine salts employed may be alkyloamine salts of acids containing mono-cyclic or poly-cyclic groups and they may be salts of substituted or unsubstituted aromatic mono or poly carbocyclic acids including salts of acids in which one or more of the hydrogen atoms of the nucleus or a side-chain are replaced by groups such as the hydroxyl group, the nitro group, the amino group, an alkyl group or by halogens, for instance, chlorine, or acids in which the hydrogen atom of an hydroxyl group attached to the nucleus or to a side-chain is substituted by an acyl or by an alkyl or aryl group.

Thus, alkyloamine salts of monocarboxylic acids in which the carboxylic group is directly connected to the aromatic nucleus may be employed as may also be acids in which the nucleus is connected through a saturated or unsaturated side-chain with a carboxylic group.

Further, there may be employed in accordance with the invention alkyloamine salts of acids in which an aromatic acyl group is connected with an amino aliphatic acid.

As examples of acids containing a carbocyclic group, the alkyloamine salts of which may be

used in accordance with the invention, the following are given:

Benzoic acid and its homologues, and derivatives, the toluic acids and the like; or chloro- or nitro-benzoic acids or anthranilic acid and the like;

Salicylic acid and its derivatives and homologues such as thiosalicylic, acetylsalicylic; gallic, tannic acids, or tannin and the like;

Homologues and derivatives of phenylacetic acid, for instance amino-phenylacetic acid, or hydrocinnamic acid and the like;

The phthalic acids, their homologues and derivatives such as mellitic acid, phthalimide and the like.

The alkyloamine salts of poly-carboxylic acids employed in accordance with the invention may be those in which all or only certain of the carboxylic groups are combined with alkyloamine residues and in the latter case the remaining carboxylic groups may be combined with other organic or with inorganic bases.

The alkyloamine salts may be compounds of mono-, di-, or trialkyloamines, for instance, mono-, di-, or triethanolamines or propanol- amines and the like.

Generally, however, salts of commercial ethanamine will be used.

In the production of compositions in accordance with the invention, the alkyloamine salts may be first formed and then added to the other constituents of the composition, for instance, to a preformed body of soap or the salts may be formed in situ in the composition.

Thus, for example the soap may be mixed with an alkyloamine and the acid employed for forming the salt of the alkyloamine added at the same time or subsequently.

The following particulars are given by way of example to illustrate suitable manners of carrying the invention into effect:

Example 1

150 parts of commercial triethanolamine which consists of a mixture of mono-, di-, and tri-hydroxy-mono-, di- and tri-ethylamine, the latter compound predominating, are warmed slightly and mixed with 125 parts of benzoic acid; heating and agitation is continued until the acid dissolves in the triethanolamine to a pale yellow semi-liquid mass which solidifies on cooling. This compound namely the benzoic acid salts of the alkyloamines which is more or less crystalline, is dissolved in warm water or in warm glycerinated water, that is water containing a small percent-

age of glycerine, and incorporated with soap in a proportion equal to about 20 times the weight of the alkyloamine salt, such incorporation taking place during any stage of the manufacture of the soap. The agent can be added during or soon after the boiling process or it can be crutched-in or it can be mixed with the soap chips or flakes during milling operations, or, again, it can be added to the perfume with which the soap is to be scented.

Example 2

140 parts of salicylic acid are stirred into 150 parts of commercial triethanolamine and warmed until the acid dissolves to a yellow syrup after which about 30 parts of boric (boracic) acid are incorporated, and mixed and heated until a homogeneous viscous liquid is obtained. This product is mixed with from five to ten times its weight of soap in the manner indicated in the previous example.

Example 3

150 parts of salicylic acid, British pharmacopoeia, or its equivalent weight of commercial product, are mixed thoroughly with 150 parts of triethanolamine until the salicylic acid dissolves in the triethanolamine forming a homogeneous viscous to semi-solid mass.

Example 4

136 parts of pure phenylacetic acid or its equivalent weight of the commercial acid are mixed with warm triethanolamine resulting in a viscous to semi-solid mass which solidifies on cooling. This product can be used also as a substitute for soap perfume.

Example 5

150 parts of triethanolamine are mixed with 85 parts of phthalic acid and agitated until dissolved giving a straw coloured viscous liquid.

Example 6

150 parts of triethanolamine are mixed, if necessary with the aid of heat, with 170 parts of phthalic acid and stirred until solution is effected.

Example 7

The product of the foregoing example is mixed

with a metallic hydroxide or a metallic compound, for example the 316 parts of the agent are combined with 40 parts of sodium hydroxide, or with 100 parts of potassium carbonate.

Example 8

205 parts of potassium hydrogen phthalate are mixed with 150 parts of triethanolamine with the aid of heat if necessary until combination results.

Example 9

208 parts of naphthalene sulphonic acid are mixed with 150 parts of triethanolamine and heated until dissolved.

In connection with Examples 3 to 9 it is to be remarked that the product obtained in accordance with these examples is mixed with soap in suitable proportions or otherwise worked up into compositions of matter in combination with other materials and particularly such as are of a sap- onaceous character.

By the incorporation of alkyloamine compounds in accordance with the invention in soaps formed in such manner as to give a quick but evanescent lather the lather given by such soaps may be stabilized.

In conclusion it is to be pointed out that the invention is concerned with the production of soaps in the form in which they are normally sold and it extends merely to the incorporation in such soaps of the salts of alkyloamines as distinguished from the esters, amides, or ester-amides formed by the interaction of alkyloamines and acids.

I claim:

1. A soap consisting essentially of an alkali metal salt of a higher fatty acid, associated with from 5 to 20 per cent of an alkyloamine salt of salicylic acid, as a retarder of hydrolysis.

2. A soap consisting essentially of an alkali metal salt of a higher fatty acid in association with an alkyloamine salt of an aromatic carboxylic acid in a proportion of between 5 and 20 per cent of the amount of the former, whereby the degree of hydrolysis of the alkali metal salt when dissolved in water, is reduced.

JACK LEBEN.
